FORCE CUP FOR CLEANING DRAIN PIPES
AND THE LIKE

Eben L. Scott, Mission, Kans.

Application June 17, 1949, Serial No. 99,614

9 Claims. (Cl. 4—255)

1

This invention relates to a force cup for cleaning drain pipes, and covers an invention disclosed but not claimed in my application, Serial No. 591,455, filed May 2, 1945, matured as Patent No. 2,473,452, dated June 14, 1949.

The most common device for cleaning drain pipes is a rubber force or vacuum cup that is placed over the inlet of the drain and manipulated by a handle to exert alternate pressure and suction forces on the obstruction. Such cups are usually made relatively thick to provide the desired action and the rubber soon breaks under the constantly reversing flexure of the wall of the cup when the device is in use.

It is therefore a principal object of the present invention to provide a force cup of this character with a reinforcing member to accomplish better action and longer life of the cup element.

It is also an object of the invention to provide for ready replacement of the cup element within the reinforcing member when the cup element becomes worn with use.

In accomplishing these and other objects of the invention, I have provided improved structure, the preferred form of which is illustrated in the accompanying drawing wherein:

Fig. 1 is a perspective view of a pipe cleaning device embodying the features of the present invention.

Fig. 2 is a similar view but showing the elements of the device in spaced relation with a part of the cup wall broken away to better show the shape of the rim thereof.

Fig. 3 is an enlarged fragmentary perspective view to better illustrate the latch for connecting the rim of the cup element with the reinforcing member.

Fig. 4 is a fragmentary perspective view of a modified form of connection between the rim portion of the cup element and the reinforcing member.

Fig. 5 is a section on the line 5—5 of Fig. 4.

Referring more in detail to the drawings:

1 designates a pipe cleaning device embodying the features of the present invention, and which includes a substantially hemispherical force and suction cup 2, formed of relatively soft resilient material such as rubber and having a rim 3 adapted for sealing contact circumferentially of a drain opening. The cup 2 has a socket portion 4 projecting from the convex side to receive the end 5 of a rod-like handle 6.

In order to reinforce the cup, it is enclosed within a cage-like member 7 including a split band 8 encircling the socket portion 4 of the

2

cup and having ears 9 and 10 at the ends thereof to pass a fastening device such as a bolt 11 to draw the ears together and contract the band about the socket for assuring anchorage of the cup on the handle. The clamping band 8 has outwardly and downwardly extending fingers 12 formed of resilient material and which are connected at the ends by a band 13 adapted to be received within an annular groove 14 opening upwardly within the rim 3 which encircles the hemispherical wall portion 15 of the cup. The ends of the fingers 12 may be attached to the respective bands in any suitable manner, as for example by spot welding, as indicated at 16 and 17 Fig. 2.

The rim of the cup 3 is anchored to the band 13 for preventing displacement thereof from the groove 14. The fastening means includes tab portions 18 registering with the respective fingers 12 of the cage-like reinforcing member and having sleeve portions 19 arranged transversely with respect to the fingers 12 and having axial openings 20 therethrough for passing the hook end 21 of latches 22. The latches 22 have shank portions 23 that terminate in eyes 24 which are pivotally connected with the fingers 12 by fastening devices such as rivets or the like 25. Fastening devices 26 have heads 26 to engage the outer sides of the eyes 24 as shown in Fig. 3.

The handle may be provided with a longitudinal passageway or channel 27 as disclosed in the above mentioned patent to pass a tape 28 which operates through the cup to manipulate a spoon or a spear element 29 (Fig. 2) to cooperate with the cup in dislodging an obstruction when the cup is in use.

In assembling the cup and the reinforcing member, the band 13 is passed over the socket portion of the cup to seat within the groove 14, care being taken to register the fingers 12 with the tab portions 18. The latches 22 are then swung on their pivotal mountings 25 to engage the hook ends 21 thereof within the axial openings 20 of the tabs. The handle 6 is then applied in the socket portion 4 of the cup 2 and the band 8 is contracted upon tightening of the bolt 11 so as to firmly connect the cup with the handle.

In using the device constructed and assembled as described for cleaning a drain of an obstruction the spoon or spear 29 is withdrawn into the cup as disclosed in the above mentioned application, and the cup 2 is placed over the drain so that the spear or cup end of the tape may be projected therethrough. Pressure is applied to the cup 2 through the handle 6 to effect alter-

nate collapse and expansion thereof for producing alternate suction and pressure on the obstruction while it is being acted upon by the spear element 29 of the tape to expedite disengagement of the obstruction. When the cup element is in operation, the reenforcing element 7 flexes to provide the desired action and the resiliency in the fingers 12 assists in restoring the cup to its original shape.

It is also obvious that the cage-like reenforcing member provides sufficient backing to reinforce and prevent rapid wearing out of the cup due to the reverse flexing movement thereof when the device is in use. In case the cup should become worn or cracked after considerable use, the latches 22 are disengaged from the tabs 18. The nut on the bolt 11 is then loosened to permit withdrawal of the cup from the handle 6 and to allow disengagement of the band 8 from the socket portion 4 of the cup. The reenforcing member 7 may then be withdrawn from the cup and a new cup placed therein as above described.

The form of the invention illustrated in Figs. 4 and 5 differs from that illustrated in Figs. 1, 2 and 3 only in the method of attaching the rim of the cup to the cage-like reenforcing member. In this form the band portion 13, which engages in the groove 14 of the cup rim 3, is provided with rivet-like studs 30 that are arranged in spaced circumferential relation and are adapted to project through openings 31 of the flange 32 of the cup. The studs 30 have ball-like heads 33 which effect stretching of the openings 31 when the heads 33 are passed therethrough and engage the outer face of the cup rim when the material contracts about the studs 30 as shown in Fig. 5. In assembling this form of the invention, the reenforcing member is passed over the cup as previously described with the band portion 13 thereof entering the recess 14 in which position the heads of the studs may be pushed through the openings 31.

From the foregoing it is obvious that I have provided a force cup with a reinforcement which controls the action of the cup and provides for longer life of the cup. When the cup does become worn or cracked it is readily removed and replaced with a new cup.

What I claim and desire to secure by Letters Patent is:

1. A device of the character described including a resilient cup having a coaxial socket-like projection for securing a handle and having an annular rim, a reenforcement member including a band encircling said projection, an annular band engaging said rim, and resilient members interconnecting said bands.

2. A device of the character described including a resilient cup provided with a coaxial socket-like projection and having an annular rim, a reenforcement member including a band encircling said projection, an annular band engaging said rim, and resilient members interconnecting said bands, said members having a shape corresponding to the cup.

3. A device of the character described including a resilient cup having a coaxial socket portion extending therefrom and having an annular rim, a reenforcement member including a band encircling the socket portion, an annular band engaging said rim, resilient members interconnecting said bands, and latch means for anchoring the last named band in engagement with said rim.

4. A device of the character described including a resilient cup having a coaxial socket portion extending therefrom and having an annular rim provided with apertured means, a reenforcement member including a band encircling the socket portion, an annular band engaging said rim, resilient means interconnecting said bands, and hooks having shanks pivotally connected with the band connecting means and engaging said apertured means for anchoring the last named band in engagement with said rim.

5. A device of the character described including a resilient cup having a coaxial socket portion extending therefrom and having an annular rim provided with an annular recess and having tabs on outer sides of said recess, a reenforcement member including a contractable band encircling the socket portion, an annular band engaging in said recess, resilient means connecting the bands, latch means pivotally connected with the band connecting means and having hooks engaging in apertures of said tabs.

6. A device of the character described including a resilient cup having a coaxial socket portion extending therefrom and having an annular rim provided with an annular recess, reenforcement means for said cup including a contractable band encircling the socket portion, an annular band engaging in said recess, and resilient members interconnecting said bands.

7. A device of the character described including a resilient cup having a coaxial socket portion extending therefrom and having a rim provided with an annular recess, a reenforcement means for said cup including a contractable band encircling the socket portion, an annular band engaging in said recess, resilient member connecting with said bands, and latch means for anchoring the last named band in said recess.

8. A device of the character described including a resilient cup having a coaxial socket portion and an annular rim provided with an opening recess opening in the direction of the socket portion, a reenforcement member including a band encircling the socket portion, an annular band engaging in said recess, resilient members connecting the bands, studs carried by said band and having portions engaging in openings in said rim.

9. A device of the character described including a resilient cup having a rim, a reenforcement member for said cup having portions engaging said rim, studs on said portions of the reenforcement member and having portions engaging in openings in said rim of the cup.
